WILBUR L. WRIGHT, OF FULTON, NEW YORK, ASSIGNOR TO OSWEGO FALLS CORPORATION, OF FULTON, NEW YORK, A CORPORATION OF NEW YORK.

BOTTLE CLOSURE DISK.

Application filed March 15, 1928. Serial No. 262,018.

This invention relates to closure disks of the so-called milk bottle cap type composed of a flat disk cut from sheet pulp, paper or felted fibrous material, sometimes called pulp or paper board, that is usually from about, say, forty to about, say, seventy thousandths of an inch in thickness having parallel hard or calendered top and bottom surfaces integral or in one piece with an intervening 5 integral mass of felted fibers, that possesses the peculiar characteristic of being capable of splitting or tearing, under the application of the necessary force, along a plane between and parallel with the top and bottom 10 surfaces of the sheet or the disk cut therefrom.

This peculiar splitting characteristic of such sheet paper material has heretofore been taken advantage of by me, in the formation 20 of an imperforate flat milk bottle cap having a panel-like portion that can be picked up at one end and split from the disk to form a pull tab that is integral at its base with the body of the disk and at its base or hinge portion 25 is of the full thickness of the disk so as to withstand the pulling force exerted on the disk through the tab to extract the disk without tearing the tab from the disk, and which tab carries up when elevated a relatively 30 short and narrow bottom plug portion that opens a pouring and drinking tube opening through the disk into the bottle. The disk was thus formed with a tab portion located 35 remote from the perimeter of the disk by an approximately U-shaped top incision extending down about half way through the disk and a relatively short and narrow bottom incision extending up about half way through the disk and located longitudinally 40 of and about centrally between and spaced from the vertical planes of the longitudinal side slits of the top incision, also that the top and bottom incisions do not meet and are non-aligned, with the inner end of the bottom 45 incision located outwardly beyond or short of the inner end of the top incision. The pull tab when split from the disk and lifted presented a relatively short and narrow portion 50 the full thickness of the disk with a top relatively thin overhanging flange at the longitudinal sides and free end of the tab

having a raw bottom surface where split from the portion of the disk outside of the side and end portion of the bottom incision. The peculiar splitting characteristic of the 55 sheet paper material that was utilized in this closure disk hereinbefore described caused certain serious difficulties that developed in the public use of such disk, namely; the tendency of the top half of the tab portion to split from the plug portion or bottom half thereof and thereby leave said plug in and closing the disk, resulting in the formation of a thin pull tab that was not capable of serving as a disk extracting pull tab because it would tear from the disk under disk 60 extracting pull, as such tab was not at its base the full thickness of the disk. The pull tab, thus often ceased to function as a pull tab and to open up a pouring and tube opening through the disk, and I have discovered that this difficulty is due to the tendency of the pull tab itself to split longitudinally from the bottom or plug portion of such tab owing to the difficulty of picking up the full thickness of the top pick up end of said tab and 65 of always inserting the finger nail under said end and because of the frictional hold of the bottom or plug portion of the tab in the bottom portion of the disk and the resistance 70 thereof against elevating and because of the thickness and stiffness of the hinge connection between the body of the disk and the base of the full-thickness tab and the consequent tendency of the upper portion of the full-thickness tab to swing up on a slightly different axis from the lower portion thereof with a resulting differential longitudinal fibre separating or splitting pull or strain on the upper and lower longitudinal tab portions. For years efforts have been made to 75 solve the problem within the limitations prescribed by manufacturing costs and the necessary low selling price and trade requirements against complications, but without 80 success, until the happy thought of the instant invention.

An object of the invention is to so improve the closure disk of the type hereinbefore described as to overcome the difficulties set forth and assure the functioning of the tab as a 100

full-strength pull tab and to always open the pouring and tube opening through the disk, in a simple and efficient manner.

With this and other objects in view, the invention consists in certain, novel features and in formations and structures as herein-after described and specified.

Referring to the accompanying drawings, forming a part hereof:

10 Fig. 1 is a top plan of a paper material milk bottle cap or closure disk showing an example of an embodiment of my invention.

Fig. 2 is a section, on an enlarged scale, on the line 2—2, Fig. 1.

15 Fig. 3 is a top plan of the disk of Fig. 1, with the pull tab split upwardly from the body of the disk and bent back.

Fig. 4 is a section on the line 4—4, Fig. 3.

Fig. 5 is a bottom plan view of the disk 20 of Fig. 1.

Fig. 6 is a top plan of a paper material closure disk embodying my invention in another form.

Fig. 7 is a detail section on the line 7—7, 25 Fig. 6.

Fig. 8 is a top plan of a paper material closure disk showing another form of my invention.

Fig. 9 is a detail section on the line 9—9 30 Fig. 8.

Fig. 10 is a top plan of a paper closure disk showing my invention in still another form.

Fig. 11 is a top plan of a paper closure disk showing a further form of my invention. 35

Fig. 12 is a detail section on the line 12—12, Fig. 11.

The flat paper disks or so-called milk bottle caps 1, illustrated by the several figures 40 of the drawings, are all composed of sheet fibrous material such as hereinbefore described, possessing the capacity to split as has been explained.

Each disk is incised vertically and part 45 way through downwardly through the top and upwardly through the bottom, by top incisions 2, and bottom incisions 3, to provide each disk with a pull tab portion 4, when split from the disk and elevated, as in

50 Figs. 3 and 4. While such pull tab portion remains parallel with the top and bottom surfaces of the disk and integral with or an unbroken part of the disk, the top incision 2, outlines a top panel 5, at the top of

55 the disk which is the top of said pull tab portion, while the bottom incision 3, outlines a relatively narrower and shorter panel 6 on the disk bottom which is the bottom, or underside of the plug, of said pull tab portion.

In the examples shown, the pull tab portion 60 is located entirely within the boundary of the disk established by its perimeter, and hence the tab portion and its base junction with the body of the disk are remote from the

surrounding edge of the disk. The incisions are more or less U-shape in form to establish the junction of the pull tab base with the disk body to provide the hinge 7, of the full thickness of the disk at which the material bends when the tab is split and elevated and which is of the required tensile strength to extract the disk from the bottle mouth under the extracting pull of the tab, without separating or causing the disk to split through its edge. These incisions also provide at the top, the relatively vertically thin inner or pick-up end 8, of the tab, and at the bottom, the inner end of the reduced or plug portion of the tab. 80

The bottom incision is narrow and shorter than the top incision to leave unsevered unbroken internal portions of the disk intervening between the inner ends of the cuts of said incisions, whereby the tab portion 85 remains an integral part of the disk and parallel with the top and bottom surfaces thereof, until the tab is split up, all approximately as generally disclosed by my Patent No. 1,403,532 of Jan. 17, 1922.

The relatively thin pick-up end of the tab portion at the top of the disk can be defined by a top recess 9, (Figs. 1, 2, 3, 4, 6, 10, 11, 12) formed by cutting out and removing a plug of the paper material in thickness about 95 equal to the depth of cuts 2, which intersect said recess, so that a vertical wall of the recess is formed by the exposed edge of the pick-up end, and the splitting of said end of the tab portion can be initiated by the nail 100 of the finger inserted in the recess so that the pick-up end can be raised sufficiently to be pinched between the fingers to pull the tab up, stripping the same from the disk back to hinge portion 7. 105

If the tab pick up end is not defined by a transverse picked out recess, it might be formed by an embossing tool, or it can be defined as in Figs. 8 and 9, by the cross portion 2^a, of the top incision 2, joining the diverging longitudinal side cuts of the U-shaped incision. 110

The problem and difficulty hereinbefore set up has been solved and such difficulty has been overcome, by the application of an 115 added element or means, whereby the pull tab portion of the flat liquid tight disk is stitched through from top to bottom to tie the top, bottom and intervening mass of the tab portion together, to rise intact when 120 stripped and elevated from the remainder of the disk, to thereby assure the formation of the drinking tube and pouring opening through the disk and the provision of a pull tab for extracting the disk. 125

This stitching can be accomplished by various means or by stitching elements of various formations and locations in or along the said pull tab portions, some of which elements and locations I have disclosed in the 130

drawings for illustrative but not in all events for purposes of limitation, as various other formations and arrangements might be resorted to without departing from the 5 spirit and scope of my invention.

For instance, I show the stitching formed by riveting or the like, whether by U-shaped or straight length metal staples, although I do not wish to so limit all features of my invention. 10

In Figs. 1 to 6, both inclusive, a very small or thin preferably flexible wire U-shape staple 10, is driven down through flat pull tab portion of the disk with the lower ends 15 of its legs clinched or doubled up against the under side of said portion of the disk. The top length of this staple is arranged longitudinally and approximately centrally of and on the top face or panel 5, of the tab portion, in this particular example, approximately 20 throughout the length thereof, and the staple, in this example, at its inner end (radially of the disk) extends to the pick up end 8, of the tab portion with its leg at that end extending down through the disk 25 approximately outside of or through the cross portion of the bottom incision 3, and then clinched back onto the bottom of the plug portion of the tab part, preferably so that the inner end leg 11, of the staple is 30 somewhat rounded to avoid puncturing or injury to the finger when initiating the splitting and uplifting of the tab pick up end. This arrangement of the staple end, at the 35 tab pick up end, provides a guide for the finger nail in picking up the tab end and stiffens said end in such manner that the tab can be quickly split and rocked up, intact and bodily with its plug 6. In fact, as shown 40 by the stitching or staple 10, 11, Figs. 8 and 9, the location of the end 11, of the staple at and forming a pick up guide for the pick up end of the tab, avoids the necessity of providing the depression 9, or other recess to expose the pick up edge of the tab part for the 45 insertion of the finger nail. The curved depending end 11, of the staple forms a guide and pick up for the finger nail by means of which the tab can be easily and quickly elevated and split from the disk, and the pick up end of the tab portion is thereby rendered accessible for elevation, without exposing the tab edge by a recess or cut enlargement. 50

However, the stitching from top to bottom of the tab portion can be accomplished by a U-shaped rivet or staple 12, arranged transversely of the tab portion intermediate its edges and its hinge portion and pick up 55 end, as in Figs. 6 and 7; the staple being driven through the tab portion with its legs clinched to the bottom thereof and its longitudinal length on the top thereof.

Again, the U-shaped rivet or staple 13, Fig. 10, can be arranged longitudinally of

the tab portion remote from its pick up end, and can extend outwardly beyond the hinge portion or base of the tab portion, or can terminate short thereof, with its legs driven down through the disk and turned or clinched to the under side of the tab portion, or one on the under side of the tab portion and the other wholly on the disk outwardly beyond the under side of the plug portion or wholly or partly on said plug portion. 75

Again, as in Figs. 11 and 12, the stitching through the tab portion of the disk can consist of a single or straight length rivet or staple 14, passed through the tab between its sides and remote from its end and hinge 80 portion and clinched or upset against the top and bottom surfaces of said tab portion.

In any event, however, the tab portion is stitched through, the described difficulty is overcome, and the tab is stiffened and 85 strengthened and the splitting and elevation thereof is facilitated, and the tab is maintained against splitting longitudinally within itself, and the desired proper uncovering of the opening through the disk is assured on 90 splitting of the tab and elevation thereof to form a disk extracting pull tab.

The milk cap or closure disk of my invention is tight against leakage therethrough before the pull tab has been split up, and furthermore is without such top and bottom projections as will prevent the use thereof in automatic bottle capping machinery. The stitching elements are shown in the drawings exaggerated in size relative to the disk. 100

What I claim is:—

1. A closure disk of fibrous material incised part way through from the top and bottom to outline a pull tab portion capable of being picked up from one end and split from the disk toward its base junction with the disk to provide an opening through the disk and a disk extracting pull tab having its base junction with the disk of the full thickness of the disk, and stitching extending transversely 105 and completely through said tab portion of the disk and elevating with said tab. 110

2. A closure disk of fibrous material closed against liquid leakage therethrough and incised to provide a tab portion capable of splitting from the disk and elevation to provide a drinking tube opening, and stitching extending vertically through said tab portion from the top to the bottom thereof and holding together the top, bottom and intermediate portions thereof against separation by splitting. 115

3. A closure disk of thin flat single-thickness fibrous paper material capable of splitting in planes between and approximately parallel with its top and bottom surfaces, said disk incised part way through from its top and bottom to provide a pull tab portion capable of being lifted and split to provide a disk extracting pull tab and an opening through the disk, the top, bottom and intermediate 125 130

- portions of said pull tab portion being secured together to prevent splitting of the pull tab during splitting and lifting thereof from the body of the disk.
5. 4. A closure disk of sheet paper material that is capable of splitting between its top and bottom faces, said disk incised to provide a pull tab portion forming an unbroken part of the disk and capable of being initially split 10 and lifted at one end from the disk, and a stitching element extending transversely through said tab portion and forming a finger nail guide at said end of said portion.
- 10 5. A closure disk of sheet paper material

that is capable of splitting between its top 15 and bottom faces, said disk incised to provide a pull tab portion forming an unbroken part of the disk and having a pick-up end adapted to be engaged and lifted by the finger nail to split and elevate the tab portion from 20 the body of the disk, and a staple driven through said tab portion and stiffening said pick-up end.

In testimony whereof I have hereunto set my hand at Fulton, New York, this 14th day 25 of March, 1928.

WILBUR L. WRIGHT.
